UNITED STATES PATENT OFFICE

JOHANN MAHLER, OF AUGSBURG, GERMANY, ASSIGNOR TO THE FIRM: MASCHINEN-FABRIK AUGSBURG-NUERNBERG, AKTIENGESELLSCHAFT, OF AUGSBURG, GERMANY, A CORPORATION OF GERMANY

FUEL PUMP OF INTERNAL-COMBUSTION ENGINES

Application filed April 11, 1925, Serial No. 22,373, and in Germany May 9, 1924.

This invention relates to fuel pumps for internal combustion engines operating with solid fuel injection.

It is one of the principal objects of this invention to provide a fuel pump of this type having an efficient regulating means.

It is another object of this invention to provide a fuel pump having means for collecting the fuel leakage in said pump, and for returning the collected fuel to a reservoir.

These and other objects of the invention will be apparent from the following description taken in connection with the accompanying drawing.

To regulate the degree of admission with fuel pumps for internal combustion engines, it is a well known fact that the fulcrum of the lever which influences the cut-off or relief valve must be adjusted. It is further known that the admission of fuel can be regulated in a similar way by adjusting the fulcrum of the driving lever of the pump.

This invention uses both these regulating arrangements and connects the two regulating levers which are mounted on eccentric shafts and which influence the cut-off or relief valve and the pump plunger by a linkage which transfers the movement from the cam-shaft to the pump plunger, and at the same time also allows an independent adjustment of the degree of fuel admission as well as the beginning or time of the fuel injection.

The pump drive is enclosed in a casing, and the pump casing is used to collect the fuel which leaks past the pump plunger and the relief valves and is led from there to a reservoir for further use.

The invention is illustrated in the accompanying drawing, in which the single figure is a vertical section through the fuel pump, and in which "a" is the pump plunger, "b" the relief valve of the fuel pump and "c" the driving cam of the pump. Between this cam disc and the pump plunger, two regulating levers "d" and "e" are arranged, which are mounted upon eccentric shafts "f" and "g" respectively and which are connected by a link-

age "h". The lever "d" is used to regulate the amount or degree of fuel admission by turning the shafting "f" by means of a governor, the fulcrum of the lever being either raised or lowered in the direction of the arrow so that the stop "i" either retards or advances the relief valve "b". The lever "e", however, can in a similar way be adjusted longitudinally by turning the shaft "g" so as to advance or retard the engagement of the roller "j" by the curve or rise of the cam disc, thereby altering the beginning of the fuel admission, with relation to the stroke or cycle of engine operation.

During operation of the pump, fuel is admitted to the pump chamber from the suction chamber "w" controlled by a suction valve "t". On the suction or down stroke of the pump plunger "a" the suction valve "t" opens to admit fuel.

At the commencement of the pressure or up stroke of the plunger the relief valve "b" is closed and consequently the plunger "a" serves to immediately force fuel through the passage "r" to the engine cylinders. This action is rendered possible by virtue of the particular form of driving mechanism disclosed, the rise of the cam "c" being such that the pump plunger is immediately given a substantially constant speed of such velocity that the injection fuel is at once placed under conditions of pressure suitable for injection. Consequently the injection may commence substantially at the beginning of the pumping stroke, thereby obviating the necessity of relief mechanism for by-passing the fuel at the beginning of the stroke and while the plunger is being brought up to

such speed as will insure suitable pressure throughout the injection period. The injection of fuel is terminated by the engagement of stop "i" with relief valve "b" to raise the latter so that during the remainder of the pressure stroke of the plunger "a" the fuel is by-passed into the chamber "s", from whence it passes through pressure operated valve "u" into the relief or overflow chamber "v" from where it is returned to the

fuel supply or reservoir in any desired manner.

It is to be noted that the pivot of the lever "d" is adapted to be moved in a vertical direction and has substantially no horizontal movement when the shaft "f" is rotated to adjust the same. This movement is indicated by the arrows to the left of the shaft "f". This provides a means for raising or lowering the stop "i" without imparting appreciable movement to the link "h". On the other hand the pivot of the lever "e" is arranged to be moved in a horizontal direction upon rotary adjustment of the shaft "g", so that this movement can take place without appreciably affecting the vertical position of the link "h" or the lever "d". This movement of the lever "e" is indicated by the arrows below the shaft "g". An advantage of the present invention is that by adjusting shaft "g", it is possible to advance or retard the admission of fuel with relation to the stroke or cycle of engine operation, without in any way affecting the amount or degree of fuel admission. Further, adjustment of the shaft "f" operates through parts "d" and "i" to vary the point of cut-off of the fuel, and hence the amount or degree of admission of the fuel to the engine without in any way affecting the beginning of the fuel admission with relation to the cycle of engine operation. The beginning or time of fuel injection and the degree of fuel admission are thus independently adjustable.

The pump drive is enclosed in the casing "k", the under part "l" of which is arranged for receiving the fuel which leaks past the pump plunger "a" and the relief valve "b". The fuel which is thus collected is led by the piping "m" into the reservoir "n".

Having now described my said invention, what I claim as new is:

1. A fuel pump for solid injection of fuel to an internal combustion engine, comprising means for controlling the beginning of fuel injection, and means for controlling the degree of fuel admission, said means including a plurality of adjustable members, a pump plunger actuated from one of said members, eccentric means for readily adjusting said member to vary the timing of the operation of said plunger, a cut-off valve actuated by another of said members, and means for actuating said members, both of said members being interposed between said actuating means and said pump plunger to transmit actuating movement to said pump plunger.

2. A fuel pump for an internal combustion engine of the character described, comprising a pump plunger for feeding fuel to said engine, the beginning of stroke of said pump plunger determining the beginning of fuel injection, a relief valve for

terminating the injection period and thereby controlling the degree of fuel admission, and means for actuating and controlling said pump plunger and relief valve, said means including a cam shaft, an eccentrically mounted lever, a roller carried by said lever in driving connection with said cam-shaft, a second eccentrically mounted lever, an adjustable stop carried by said second-named lever and adapted to cooperate with said relief valve to actuate the same, a roller carried by said second-named lever in driving connection with said pump plunger, and a driving interconnection between said levers.

3. A fuel pump for an internal combustion engine of the character described, comprising a pump plunger for feeding fuel to said engine, the beginning of stroke of said pump plunger determining the beginning of fuel injection, a relief valve for terminating the injection period and thereby controlling the degree of fuel admission, a cam-shaft for operating said pump plunger and relief valve, and adjusting means interposed between the plunger and the cam-shaft for varying the time of fuel injection in relation to the cycle of engine operations and independently varying the timing of the relief valve, said adjusting means comprising a pair of substantially parallel adjacent arms each eccentrically mounted at one end, an operable interconnection at their other ends, and means for adjusting the eccentric mountings to move the pivot axes in directions at substantially right angles to each other, the eccentric mountings being located substantially in a line parallel to the pump plunger and at right angles to the said arms.

4. A fuel pump for solid injection of fuel to an internal combustion engine, comprising means for independently controlling the beginning of fuel injection and the degree of fuel admission, said means including a pair of adjustable members, a pump plunger actuated by said members, a cam for actuating said members, both of said members being interposed between said cam and said pump plunger and both effective to transmit actuating movements to said pump plunger, and means for adjusting one of said members to adjust the beginning of fuel injection without affecting the degree of fuel admission.

In testimony whereof I have affixed my signature.

JOHANN MAHLER.
